CLAIM

The ornamental design for a mosquito killer lamp, as shown and described.

DESCRIPTION

FIG. 1 is a front perspective view of a mosquito killer lamp, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the mosquito killer lamp, which form no part of the claimed design.

The unshaded areas between broken and solid line form no part of the claimed design.

1 Claim, 8 Drawing Sheets
